CLAIM

The ornamental design for an automobile wheel or replica thereof, as shown and described.

DESCRIPTION

FIG. 1 is a perspective view of an automobile wheel or replica thereof illustrating our ornamental design; FIG. 2 is a front elevation view thereof; and,

FIG. 3 is a top plan view and right-side elevation view thereof the bottom plan view and left-side elevation view being mirror images respectively.

The broken lines shown in the drawings are for the purpose of illustrating environmental structure and no part of the claimed design.
